CONSTANT TENSION WINDING

Robert P. Lathrop, Chevy Chase, Md., assignor to
 E. I. du Pont de Nemours and Company, Wil-
 mington, Del., a corporation of Delaware

Application September 20, 1950, Serial No. 185,837

7 Claims. (Cl. 242—45)

1

This invention relates to an apparatus and method for winding yarn at constant tension and, in particular, relates to an apparatus for converting a pirln wind-up to constant tension spool wind-up.

In the commercial production of synthetic filaments, yarns, monofilaments and the like, several processing steps are generally required in order to develop to an optimum the inherent desirable properties of the resinous structure. In the course of this processing the yarn must be wound on a package, such as a bobbin or pirln, at least once and generally more often. For example, yarns dry spun from solutions of synthetic high polymers are generally wound on a package, subsequently creel and drawn several times their original length and finally wound onto a shipping package. In some cases where special twist is required, additional windings are necessary.

During winding on a bobbin or pirln the tension on the material being wound usually changes progressively as the bobbin fills up and the diameter increases. Particularly in downtwister pirln wind-up, low uniform winding tensions are incompatible with large ratios of inside to outside package diameters and high feed speeds. The higher the feed speed, the greater will be the tension increase in winding the outside as compared with the inside of the package unless the over-all winding tension is greatly increased by greater spindle speed, other dimensions remaining constant. Constant tension winding is necessary to avoid stretching and to produce a uniform package of yarn having uniform physical properties throughout the package.

In the preparation of some synthetic yarns it has been found advantageous to wind the as-spun yarn on a spool-type cylindrical pirln by means of a downtwister yarn take-up. When spinning certain types of yarns at speeds up to 300 yds./min., the downtwister type take-up is quite satisfactory since the tension can be made to remain suitably low and fairly uniform throughout the winding. However, when higher spinning speeds are used at low winding tension, the winding tension increases rapidly with package diameter. Especially with freshly spun yarns which are weak and readily extensible this increase in winding tension with package diameter cannot be tolerated. The resulting yarn has non-uniform physical properties and poor denier uniformity.

Accordingly, it is an object of this invention to provide an apparatus for converting standard downtwister take-up to a traverse bobbin winder

2

which will wind yarn, film, ribbons, etc. at constant tension. It is an object of this invention to provide a means for winding yarn under constant tension. It is a particular object to provide a means for winding yarn at high speeds at low uniform tension. It is still a further object to provide for the preparation of much larger packages of yarn with no major change in design of the take-up. Another object is to provide a spool winder which maintains constant winding tension through controlled torque applied to the spool as opposed to surface drives and variable speed drives. Other objects will become obvious from the description of the invention which follows.

The objects of this invention are accomplished by the provision of an adapter assembly which fits snugly over a spindle of the type commonly used on a downtwister type take-up. The 20 adapter assembly comprises an inner shell which supports a tubular outer shell on ball bearings, the inner shell being driven by the constant speed spindle and containing a magnetic clutch which induces eddy currents in a drag member, located 25 within its field, attached to the outer shell, whereby the outer shell is caused to rotate. By proper choice of the spindle speed it is possible to wind filaments, yarns, and the like on a spool supported by the adapter assembly at high speeds 30 under relatively constant low winding tension. In order to facilitate the description, reference will be had to the appended drawings which are given for illustrative purposes only and of which:

Figure 1 is a cross-section showing the general arrangement of the elements of one embodiment of this invention;

Figure 2 is a sectional plan view of the magnet assembly taken on line 2—2 of Figure 1; and

Figure 3 is a cross-sectional view of another embodiment of the invention.

In Figure 1, the inner shell 2 fits snugly over the spindle 1 and extends into flange 6 which contains two holes 50 and 51, as shown, by means of which the inner shell is firmly attached to the 45 driving means. The outer shell 3 is concentric with inner shell 2 and fits over said inner shell, being spaced from it and freely rotatable thereon by means of ball bearings 4. The bearings 4 are preferably positioned near the top and near the 50 base of inner shell 2 as shown. The upper bearing is held in place by means of a snap ring 5 which fits into a circular recess in the inner surface of the outer shell 3. The snap ring 5 supports the outer shell 3 above flange 6 so that the 55 ring is freely rotatable. The magnet element is

positioned at the top of the inner shell 2 by means of cap screw 16 and bevel nut 11. The magnet element comprises magnet holder 7 and permanent magnets 8 positioned therein as shown in Figure 2. The magnet element rests on the backing plate 9 which positions the magnet with respect to the bearing 4. The backing plate 9 also closes the lower magnetic field. The magnet may be one unit of two poles or it may consist of several units each having two poles. It may be a permanent or an electromagnet.

The drag member 13 comprises an aluminum disc and is suitably attached to the end of bolt 12. The bolt 12 is positioned by the internally threaded support 15 which is fixed to the top of the outer shell 3 by screws 18. The distance of drag member 13 from magnet 8 can be varied by means of bolt 12. The position of the drag member 13 is maintained during operation by means of the lock nut 14 and bolt 12. The cap 16 shown in the figure is not essential and serves merely to cover the heads of screws 18 in order to eliminate any possibility of a running length of yarn snagging thereon. The holes 19 and 20 above the drag member are provided to allow some cooling of the drag member 13 if required. When the outer shell 3 rotates, particularly at high speeds, a flow of air is induced into holes 20 and out of holes 19. The pin 17, at the base, is stationary and cooperates with a longitudinal slot in the bobbin or spool to prevent any movement of the bobbin or spool relative to the outer shell 3.

In practice when it is desired to change from pirn wind-up on a downtwister machine to a high speed, constant tension wind-up, it is necessary only to fit the adapter and its essential parts, as shown in Figures 1 and 3, over the spindle and remove the traversing ring and traveler from the traversing ring rail, replacing them with a suitable traversing guide. The take-up spool, bobbin or a double flanged pirn, as shown by dotted lines 52, to be used is then fitted over the outside of the outer shell 3 of the complete adapter assembly. The take-up spool rides on the flange 53 at the base of outer shell 3. The positively driven spindle 1 rotates the inner shell 2 and the attached magnet 8. The rotation of magnet 8 induces eddy current flow in drag member 13, thereby effecting rotation of the drag member and the outer shell 3 and the spool attached thereto. When yarn is not being wound on the spool, the speed of the spool is essentially the same as the spindle speed, the small difference being caused by the resistance of the surrounding atmosphere. During the winding of a length of yarn the speed of the spool is determined by the yarn feed speed, i. e., by the speed at which the yarn is being fed to the spool from the yarn source. The rotating magnetic field generates a driving torque in the drag member which is proportional to the difference in rotational speeds of the spindle and the spool, this difference being known as the "slip." By choosing the proper relation between the spindle speed and yarn feed speed, the slip can be made nearly proportional to the package diameter. In this manner, the torque is made nearly proportional to the package diameter and the winding tension remains essentially constant. The magnitude of tension on the yarn being wound is controllable by changing the strength of the field intercepting the drag member. This can be done either by varying the air gap between the magnet and the drag member or by shunting the magnet.

In Figure 3, another embodiment of the invention, comprising a different magnetic arrangement, is shown. The inner shell 2 supports an extension 22 which narrows into stud 32. The inner shell extension 22 supports the upper bearing 23 together with the adapter 21. The bearing 23 is held in place by means of snap ring 24. The adapter 21 is held in place by the snap ring 5 which also supports the outer shell 3 above flange 6 so that is freely rotatable. The magnet 26 comprises a disc and shoulder extension which fit over the stud 32. The magnet 26 is secured in its position by nut 27 and contact with the outer shell assembly is prevented by means of the spacer 25. The magnet has positive and negative poles at opposite edges of the disc and rotation of the magnet induces eddy current flow in the cylindrical drag member 28 positioned in the upper part of the outer shell 3 by cap 29, pin 30 and set screw 31. In normal use little heat is developed by this eddy current device and consequently, the air vents shown in the apparatus of Figure 1 are not provided.

The intensity of the magnetic field intercepting the drag member 28 and the corresponding tension on the yarn being wound may be decreased by shunting the magnet 26. The magnet may be shunted readily and simply by placing an ordinary washer on the upper surface. The size of the washer determines the amount of shunting, larger washers causing greater reductions of magnetic field strength and less tension on the winding yarn. When an electromagnetic clutch is used, the field strength is varied readily by changing the current through the electromagnet. This permits adjustment of tension with ease.

Any magnetic material may be used in the magnet element, although the stronger and more permanent Alnico types are preferred. Naturally, both positive and negative poles must be at the surface near the drag member, so that eddy current flow is induced in the drag member. The drag member should be made from a metal having low electrical resistance, preferably aluminum, but it may be made of other metals, such as copper.

It has been found in using the winding apparatus of this invention that in order to wind the package of yarn under constant tension, it is necessary to choose the proper spindle speed. Since the spindle speed and the yarn feed speed are maintained constant throughout the winding, the slip will increase as the package radius increases. The winding device of this invention operates on a practically straight line relation between slip and torque. By a proper choice of spindle speed the magnet imparts a torque to the drag member which is inversely proportional to the absolute speed of the drag plate (in the speed range encountered in practice). Since this arrangement causes the torque to increase in direct ratio with the package radius, it is possible to wind yarn at constant linear feed speeds with nearly constant winding tension. The choice of the proper spindle speed necessary to wind a yarn at constant tension throughout the winding of a package of yarn is dictated by the following equation:

$$SP = \frac{F(C_1 + C_2)}{C_1 C_2}$$

wherein SP denotes the spindle speed in R. P. M.,
75 F denotes the feed speed in the linear units per

minute, and C_1 and C_2 denote the initial and final circumference of the package in the same linear units as F , and C_2 does not exceed $4C_1$. It has been found that if considerably higher spindle speeds than determined by the equation are used, the tension on the yarn, while at a higher level, decreases constantly throughout the winding of the package. On the other hand, if too low a spindle speed is used, the tension, at a lower level, will mount continually throughout the winding of the package. By using the spindle speed determined by this equation, it has been found that winding at constant tension can be achieved irrespective of yarn feed speed as long as the final package radius does not exceed four times the initial radius. At this point the equation begins to fall seriously and the spindle speed and its relation to yarn feed speed must be determined experimentally.

The apparatus of this invention has many advantages. It affords an easy means for converting twister take-up to a higher speed, uniform tension take-up (which may be operated at any predetermined tension level). It economically combines the good points of twister and spool take-ups while eliminating the disadvantages of surface driven packages or elaborate variable speed drives. Since several elements of twister apparatus, such as travelers, traveler rings, rotating balloons, balloon suppressors, and separators, are eliminated, the weight of the traversing mechanism is minimized. It provides for winding much larger packages of yarn on the same center distance with no major change in design of the take-up. The problem of yarn protection in the wind-up through applying finish is simplified since ceramic traversing guides can be used instead of metal travelers and rings. The winding of transfer tails on yarn packages also becomes much simpler. In addition, it permits the winding of water-laden yarn, which presents severe ring maintenance problems with a twister take-up.

Any departure from the procedure described herein which conforms to the principles of the invention is intended to be included within the scope of the claims below.

I claim:

1. A device for winding a filament under constant tension comprising a spindle driven at constant speed; an inner shell mounted on and driven by said spindle; bearings at the top and at the base of said inner shell; mounted on said bearings an outer shell freely rotatable in respect to said inner shell; mounted at the top of and within

said inner shell a magnet; mounted at the top of and within said outer shell a drag member located within the field of said magnet and affected thereby to rotate said outer shell upon rotation of said magnet; and at the bottom of said outer shell a flange to support a take-up unit on which said filament is wound.

2. Apparatus in accordance with claim 1 in which the said drag member is adjustably mounted so that the distance between the said drag member and said magnet may be varied.

3. Apparatus in accordance with claim 1 in which the said drag member is composed of a metal of low electrical resistance.

4. Apparatus in accordance with claim 1 in which the said outer shell contains air vents in the vicinity of said drag member.

5. A wind-up device comprising a spindle driven at constant speed; an inner shell mounted on and driven by said spindle; bearings at the top and at the base of said inner shell; mounted on said bearings an outer shell freely rotatable in respect to said inner shell; mounted at the top of and within said inner shell a magnet element comprising a magnet holder and positioned therein a magnet; mounted at the top of and within said outer shell a drag member comprising a disc of a material of low electrical resistance located within the field of the said magnet, the rotation of which induces eddy current flow in said drag member thereby effecting rotation of said drag member and said outer shell.

6. Apparatus in accordance with claim 5 in which the outer shell contains air vents in the vicinity of said drag member.

7. Apparatus in accordance with claim 5 in which the outer shell has a flange at the bottom end thereof to support a take-up unit.

ROBERT P. LATHROP.
